VACUUM MECHANISM FOR PAPER MAKING MACHINES

Arthur E. Broughton, Glens Falls, N. Y.

Application March 25, 1936, Serial No. 70,846

4 Claims. (Cl. 92—51)

This invention relates to vacuum maintaining mechanism for the suction heads of paper making machines.

In connection with the use of a plurality of paper making machines, for economical operation, it is one of the objects of the present invention to provide a single suction pump for use in maintaining the proper vacuum on groups of suction heads of all the machines and to provide suitable mechanism which, as a break occurs in the pulp web of one or more of the machines or as one or more of the machines is shut down, will permit the pump to properly act in conjunction with the remaining machines so that the remaining machines may be maintained in operation.

It is another object to provide novel improvements on my vacuum control mechanism disclosed and claimed in my United States Patent No. 1,962,477, issued June 12, 1934, and entitled "Vacuum control mechanism".

The objects and advantages of the present invention will more fully appear from the following description, made in connection with the accompanying drawings, wherein like reference characters refer to the same or similar parts throughout the various views, and, in which,

Fig. 1 is a view diagrammatically illustrating an application of the invention to a plurality of paper making machines, portions of two machines being illustrated;

Fig. 2 is a view looking from the left toward the portions of the left hand paper making machine shown in Fig. 1;

Fig. 3 is a view taken chiefly in vertical section on enlarged scale and illustrating one of the control mechanisms shown in Fig. 2;

Fig. 4 is a view looking toward the opposite side of the control mechanism shown in Fig. 3;

Fig. 5 is a vertical section through the air leg shown in Fig. 2; and

Fig. 6 is a vertical section on enlarged scale through one of the valves that are used.

Referring to the drawings, certain parts of two paper making machines A and B respectively are more or less diagrammatically illustrated. The first floor of a paper mill is designated by the numeral 1 and above this floor the two machines A and B operate. Only a few of the parts of the machine B are shown but it will be understood that this machine includes the same parts as does machine A, which is shown in greater detail.

The Fourdrinier wire upon which the mat of paper is formed at the wet end of the paper making machine is designated by the numeral 8, and

this wire runs over flat boxes 9, rollers 10 and couch roll 11. The dandy roll 12, located between the second and third flat boxes 9, is illustrated in connection with the machine A. Each of the flat boxes 9 over which the wire 8 travels is shown as being connected by a flexible connection 13 to a T-fitting 14. The water drawn from the paper web, as it is carried over the flat boxes 9 by the wire 8, is separated from the air drawn from the various flat boxes in the various T-fittings 14 and the water from each flat box runs downwardly from the fitting 14 connected thereto into a seal box 15 through a water leg or pipe 16 connected at its upper end to the lower connection of the particular fitting 14. The water legs running downwardly from the fittings 14 connected to the first two flat boxes 9 are preferably vertical pipes, in order that as the water passes down through these pipes, considerable suction will be created to assist in maintaining or to maintain without assistance the necessary vacuum in the first two flat boxes. The seal box 15 is provided with an overflow conduit 17 for the discharge of water therefrom. Air legs or pipes 18 are connected to the upper connections of the fittings 14 and these air legs run upwardly therefrom to carry off the air separated from the water in the fittings 14.

A conduit 19 runs from the couch roll 11 to the intake side of a couch pump 20 and this couch pump is provided with an outlet 21.

In order to automatically accurately maintain uniformity of vacuum pressure on the flat boxes 9, I utilize, with the flat boxes, vacuum control mechanism generally similar to that shown and described in my United States Patent No. 1,962,477 issued June 12, 1934, and entitled "Vacuum control mechanism". Inasmuch as the said vacuum control mechanism is fully described in said above referred to patent, it need only be briefly described here.

There is provided a manifold 22 located well above the flat boxes 9 for each machine and this manifold is connected to a conduit 23. The various conduits 23 of the two paper making machines A and B, together with another conduit 23 from a third machine (not illustrated) are connected to a header 24 which leads into the intake side of a single suction pump 25 which acts in conjunction with all of the various paper making machines. The suction pump 25 is equipped with an outlet 26.

The air legs 18 are connected at their upper ends to valves 27 which are, in turn, connected to the manifold 22. Castings 28 are secured to the valves 27 and these castings of substantially

open hand shape support cylinders 29. The cylinders 29 are open at their lower ends and closed at their upper ends and mounted within each cylinder is a piston 30 having a central aperture 30b through which loosely projects a sleeve 31. This sleeve is provided with an external flange 31a which cooperates with a downwardly extending ridge 30c on piston 30 adjacent the aperture 30b as do a valve member and a valve seat. Downwardly projecting lugs 30d are formed on the piston 30 which tend to guide the flange 31a to and from the ridge 30c. Having screw threaded connections with the lower end of the sleeve 31 is a stud 32 connected as by a pin 33 to the upper end of the valve stem 21a of the adjacent valve 21. This pin 33 is received within notches 28a at its outer portions, these notches being formed in a central hub of the casting 28. Accordingly, although the stud 32 may slide upwardly and downwardly relative to casting 28, this stud cannot be rotated relative to the casting. A relatively heavy coiled compression spring 35 is disposed within the cylinder 29 and bears at one end against the closed end of the cylinder and at its other end against the piston 30. A collar 36 surrounds the sleeve 31 near the upper end of the sleeve and is held from removal off this end of the sleeve by means of a pin 37. A relatively light coiled spring 38 encircles the upper portion of the sleeve 31 and bears at one end against the collar 36 and at its other end against the piston 30. Each cylinder 29 has connected thereto between its closed end and the piston 30 a pressure equalizing pipe 39 which runs downwardly from the cylinder and projects through a cap 18a at the upper end of the air leg 18 for the particular flat box 9 in connection with which the cylinder 29 is used. This pipe 39 projects downwardly through the air leg 18 to terminate in an open end within the fitting 14, as best shown in Fig. 2. A pressure gauge 40 is preferably connected to the closed end of each cylinder 29.

Each vacuum control mechanism just described acts automatically to maintain a substantially constant vacuum in the flat box 9 in connection with which it is used when the paper making machine on which it is used is in operation. Assuming that the proper vacuum is provided in the flat box 9 when the valve 27 is partly opened, the parts of the control mechanism will assume approximately the position shown in Fig. 3. The pressure equalizing pipe 39, affording communication between the fitting 14 and the cylinder 29, will cause the air pressure in the cylinder to be the same as in the flat box and the spring 38 will hold the flange 31a of sleeve 31 in tight engagement with the ridge 30c, so as to maintain the opening 30b of the piston 30 closed. Of course, the position of the valve 27 determines whether or not the pump 25 will assist in maintaining the vacuum in the flat box. If for any reason, the vacuum in the flat box 9 is increased beyond the requisite degree, i. e., the pressure in the flat box is reduced, the pressure in the cylinder 29 will be correspondingly reduced and the piston 30 will rise against the tension of spring 35. As this occurs, the spring 38 which bears against the piston 30 will cause the sleeve 31 and the valve stem 21a to rise until the valve 27 is closed and, of course, as the valve closes, the suction on the flat box will be decreased. If the vacuum still remains too great after the valve 27 has

closed, naturally the piston 30 will continue to rise against the pressure of the spring 38, thereby causing the piston to draw away from the flange 31a of the sleeve 31 to permit air to rush into the cylinder 29 through the opening 30b and break the vacuum in the flat box. Atmospheric air rushing into the cylinder 29 will then permit the spring 35 to again move the piston 30 downwardly until ridge 30c seats with the flange 31a of the sleeve, whereupon no further air can be admitted through the aperture 30b into the cylinder and the correct vacuum in the flat box will be restored either through opening of the valve 27 or by vacuum created by the passage of water through the water legs 18 connected to the flat box.

If for any reason the vacuum in the flat box 9 should fall beyond the level for which the control mechanism is set, i. e., the pressure in the flat box should increase, then the pressure in the cylinder 29 will similarly increase and the spring 35 will force the piston downwardly to push the sleeve 31 and valve stem 21a downwardly to open valve 27 farther so that the suction pump 25 may draw greater quantities of air from the air leg 18. The vacuum in the flat box accordingly is automatically controlled irrespective of outside factors that may tend to change the vacuum in the box.

Adjustment of the control mechanism to maintain any desired vacuum in the flat box is made by screwing the sleeve 31 upwardly or downwardly farther on the stud 32. For this purpose a small gear 31b is formed at the lower end of the sleeve 31 and this gear meshes with a wide pinion 41 mounted on a shaft 42 journaled in a pair of lugs 43 carried by the casting 28. The shaft 42 projects downwardly below the casting 28 and extends through a suitable bracket 44 which may be supported at any desired point 40 on the paper making machine. The lower end of the shaft 42 carries a beveled gear 45 which may be rotated by means of a beveled pinion 46 mounted on a shaft 47. This shaft may be carried to any desired point convenient to the paper making machine tender and turned by means of a handle knob 48 secured thereto. Preferably the shafts 47 for all the vacuum control mechanisms for a single machine, such as the machine A, will be carried to a central point, so that they will all be readily accessible for operation adjacent this point. Adjustment of the various control mechanisms for a single machine may thus be made at a point remote from the flat boxes.

Automatic control valves are provided in each of the conduits 23 so that in case one of the paper making machines should shut down or in case the pulp web should break in one of the machines, the single vacuum pump 25 may properly act in conjunction with the other machines to assist in maintaining the proper vacuum pressure on the flat boxes of the other machines. The automatic control valves are designated as entireties by the letter V and are shown in detail in Fig. 6.

Each valve V includes a valve body 49 which is interposed in conduit 23 between two sections thereof. The valve body 49 is preferably closed at one side by a plug 50 forming a guide for a reciprocating valve stem 51. The valve used is preferably a double seated valve and includes a U-shaped web 52 in vertical cross section which divides the valve body into two chambers, one joining the intake port of the body and the other

joining the outlet port. Valve seats 53 are formed in the web 52 for cooperation with conical valve members 54 secured to valve stem 51. Attached to the plug 50 is a casting 55 through which the stem 51 extends and this casting curves outwardly from the cap and forms a support for a cylinder 56. Within this cylinder 56 is a piston 57 mounted for reciprocation and received within an aperture in this piston is a sleeve 58 having a knurled flange at its inner end. The outer end of the valve stem 51 is screw threaded and is screwed into the sleeve 58, turning movement of the valve stem 51 being prevented by a cross pin 69 attached to the stem 15 and having its end received within notches 55a within a central hub of the casting 55. A washer 60 surrounds sleeve 58 within the cylinder 56 and this washer bears against the inner side of the piston 57. The sleeve 58 is provided with a shoulder 58a which bears against the outer side of the piston and a cross pin 61 carried by the sleeve 58 bears against the washer 60. Thus while the sleeve 58 may be turned relative to piston 57, it is not capable of longitudinal movement relative to the piston. A coiled spiral spring 62 disposed within cylinder 56 bears at one end against the closed end of the cylinder and at its other end against piston 57. The closed outer end of the cylinder is preferably equipped with a pressure gauge 63. A pipe 64 has connection at its upper end with the cylinder 56 between the piston 57 and the closed end of the cylinder and it has connection at its lower end with conduit 19 adjacent the couch roll 11.

35 Let us consider the operation of the two valves V in connection with the two paper making machines A and B. When both machines A and B are in operation, and the pulp webs on the wires 8 of the two machines are properly passing over the couch rolls 11, the couch pumps 20 will maintain the two couch rolls 11 under vacuum pressure and as the pipes 64 communicate with the conduits 19 adjacent the couch rolls 11, the chambers of the cylinders 56 will be under vacuum pressure to move and maintain the pistons 57 to the right of the position shown in Fig. 6 against the tension of the springs 62 and thereby hold the valve members 54 spaced from their valve seats 53. Accordingly, the valves V of the two machines will remain open as long as the couch rolls 11 of the machines are under proper vacuum pressure. The single vacuum pump 25 thus exerts proper suction on the two conduits 23 of both machines A and B to act with the various control mechanisms of the two machines to maintain the flat boxes 9 under the proper vacuum pressure.

Now let us assume that either the pulp web in machine A breaks or that this machine is for some reason placed out of operation while it is desirable to maintain machine B in operation. As the pulp web of machine A breaks or as machine A is placed out of operation, the pulp web will no longer seal the couch roll 11 of machine A and as a result, the pressure in couch 11 and in conduit 19 of machine A will rapidly rise, thereby causing a corresponding rise in pressure of the air within the chamber of cylinder 56 of valve V of machine A. As this occurs, the spring 62 of this valve forces the piston 57 to the left, as viewed in Fig. 6, causing the valve members 54 of valve V of machine A to engage their seats 53 to close the valve and thereby close the conduit 23. The pump 25 continues to act in conjunction with the machine B as the conduit 23 is closed,

so that vast bodies of air cannot be drawn into the pump 25 from the conduit 23 of machine A to destroy the action of the pump in connection with the machine B as would be the case if the valve V in machine A were not provided. Accordingly, the proper vacuum pressure is maintained on the flat boxes in machine B by the single vacuum pump 25, so that machine B may be operated irrespective of whether machine A continues in proper operation or not. Of course, 10 the valve V of machine B acts in similar manner to permit machine A to operate in case anything should happen to prevent the operation of machine B.

Assuming that machine A has been shut down 15 for a time and that machine A is then again put in operating condition, as the paper web carries over the couch roll 11 of machine A, it will seal this roll and the couch pump 20 of machine A will then quickly establish the proper vacuum 20 pressure within the couch roll 11 and the conduit 19 of machine A. The vacuum will then be restored in the cylinder 56 of valve V of machine A and this valve will then automatically open so that the single pump 25 will again be effective 25 in connection with both machine A and machine B.

While the operation of the pump 25 has been described in connection with but two paper making machines, it will be understood that this 30 one pump can be used with any number of paper making machines found in a paper mill, the pump acting to maintain the proper condition in the flat boxes, of all the other paper making machines as one or more of the machines is shut 35 down.

By reason of the fact that a single vacuum pump 25 can be used in conjunction with two or more paper making machines in place of one pump for each machine as is the usual practice, 40 a large saving in power in operating the plurality of machines is effected. This saving is accomplished by use of the valves V without necessitating the shutting down of other machines as any one of the machines is shut down.

45 While the pump 25 is shown and described as being used in conjunction with the flat boxes of the several machines to assist in maintaining the proper vacuum pressure on these flat boxes, it will be understood that in combination with 50 valves such as the valves V, a single vacuum pump can be used for maintaining the proper vacuum pressure on other suction heads of a plurality of machines. Although the pipes 64 are shown as being connected with the conduits 55 running from the couch roll of the different machines, these pipes could equally as well be connected to any conduits or chambers which will be maintained under vacuum pressure during operation of the machines and which will be subject to a marked rise in pressure in case of a paper break or in case of a shut down of the machines.

60 By turning the sleeve 58 of a valve V, the valve may be readily adjusted to open and close when 65 the chamber of cylinder 56 is under varying pressure.

Due to the fact that the flat boxes of the plurality of machines are maintained under substantially constant vacuum pressure by the control mechanisms therefor, it becomes possible to use but the one vacuum pump 25 for the plurality of machines when the valves V are provided.

70 It will, of course, be understood that various changes may be made in the form, details, ar- 75

angement and proportions of the various parts without departing from the scope of the present invention, which generally stated, consists in the matter shown and described and set forth in the appended claims.

5. What is claimed is:

1. The combination with a plurality of paper making machines each having a group of first suction heads, an air conduit receiving air from said first suction heads, a second suction head and means for maintaining the second suction head under vacuum pressure, of a single vacuum pump for use with the groups of first suction heads of the plurality of machines, said pump 10 receiving from all said air conduits, a valve for each machine in each air conduit and valve control means for each machine operated by the air pressure in the second suction head of that machine for opening and closing its valve, each 15 valve control means acting to close its valve as the air pressure in the second suction head of the particular machine rises above a certain pressure and acting to open its valve as the air pressure in its second suction head of the particular machine falls below the certain pressure.
2. The combination with a plurality of paper making machines each having flat boxes, an air conduit receiving air from said flat boxes, a couch roll and means for maintaining the couch roll under proper vacuum pressure, of a single vacuum pump for use with the flat boxes of the plurality of machines, said pump receiving from all said air conduits, a valve for each machine in each 20
- 25

air conduit and valve control means for each machine operated by the air pressure in the couch roll of that machine for opening and closing the said valve of that machine, said valve control means for each machine acting to close its valve as the air pressure in the couch roll of that machine rises above a certain pressure and acting to open its valve as the air pressure in the couch roll of that machine falls below the certain pressure.

3. The combination with a plurality of paper making machines, each having flat boxes, a vacuum control mechanism for maintaining the flat boxes respectively under substantially constant vacuum pressure, an air conduit receiving 15 from said flat boxes, a couch roll and means for maintaining the couch roll under vacuum pressure, of a single vacuum pump for use with the flat boxes of the plurality of machines, said pump receiving from all said air conduits, and valve 20 control means for each machine operated by the air pressure in the couch roll of the particular machine for closing the valve of the particular machine as the air pressure in the couch roll of that machine rises above a certain pressure and 25 for opening the valve of the particular machine as the air pressure in the couch roll of that machine falls below the certain pressure.

4. The structure defined in claim 1, and means for regulating each valve to vary the certain 30 pressure at which the valve will operate.

ARTHUR E. BROUGHTON.
